UNITED STATES PATENT OFFICE.

HARRY M. WEBER, OF MONTCLAIR, NEW JERSEY, ASSIGNOR TO JOHN D. CARDINELL,
OF MONTCLAIR, NEW JERSEY.

BLEACHING SOLUTION CONTAINING BROMINE COMPOUNDS.

No Drawing.

Application filed December 21, 1923. Serial No. 682,094.

To all whom it may concern:

Be it known that I, HARRY M. WEBER, a citizen of the United States, and a resident of Montclair, in the county of Essex and 5 State of New Jersey, have invented certain new and useful Improvements in Bleaching Solutions Containing Bromine Compounds, of which the following is a specification.

This invention relates to a bleaching solution prepared by incorporating phosphates and bromine compounds and to the process of making same and in the preferred form relates especially to the bromination of phosphates such as trisodium phosphate or 10 to the treatment of phosphates with or without borates with bromine in the presence of an alkaline medium. In this manner a bleaching solution is obtained which is adapted for various bleaching operations 15 such as whitening textiles, discharging colors, removing fruit stains and ink stains and the like. The solution may be used to advantage to bleach and efface handwriting in ordinary ink.

20 For many years it has been known that bleaching solutions could be produced by incorporating bromine with alkaline phosphates for example note Watt's Dictionary of Chemistry, volume 1, page 537, published 25 in 1888, where the statement appears that by the action of alkalies, alkali carbonates or phosphates on bromine water yellow strongly bleaching liquids are produced. These liquids are very unstable decomposing 30 in the air, quickly at 30°.

In the present invention I do not lay claim broadly to bleaching compositions of this general character, my invention being concerned with the preparation of a fairly 40 dilute solution by treating for example trisodium phosphate in predetermined proportions.

Another feature of the invention is the avoidance of the presence of impurities 45 which would tend to affect the stability of such bleaching compositions. As noted in Watt's Dictionary these bromine solutions are at best relatively unstable. It is recommended therefore that pure materials be employed and the water used in preparing the 50 solutions be distilled in order that iron compounds and other substances which have a catalytic effect in promoting instability be eliminated.

55 It should be understood that in the use

of this material for domestic and office purposes in removing stains, handwriting in ink and the like there must be provided a solution having reasonably good keeping qualities. The avoidance or elimination of 60 any impurities acting catalytically in the manner indicated is therefore recommended.

A composition prepared in accordance with the present invention is made by dissolving 6 per cent of trisodium phosphate in 65 water and reacting on this solution with $\frac{3}{4}$ th of 1 per cent of bromine.

Various modifications may be effected which depart to a greater or less extent from the foregoing formula. In general I prefer 70 to keep the total solids below 6 or 8 per cent in order that when treating for example paper having ink blots or handwriting in ink which is to be removed it will not on drying show a saline deposit which 75 becomes yellow or otherwise discolored in the course of time.

However it is possible to add an alkali such as caustic soda or sodium carbonate or bicarbonate to the trisodium phosphate 80 and add bromine to this solution. The bromine should be added preferably only to the point of neutrality or at most a very faint degree of alkalinity. If too strongly alkaline paper will be affected by the solution, and if on the other hand an acid reaction is shown the paper or fabric is likely to be injured. Such acid solutions also are liable to have a disagreeable odor. In any event I prefer not to have more 85 than 10 or 12 per cent of total solids in the solution.

The corresponding bleaching compositions may be made from potash salts including potassium carbonate and bicarbonate and the various potassium phosphates. It may be noted besides the orthophosphate 90 the pyro and metaphosphates may be used in some cases.

What I claim is:—

1. A bleaching solution adapted for the removal of stains, handwriting in ink and the like which comprises brominated trisodium phosphate in aqueous solution.

2. A bleaching solution adapted for the removal of stains, handwriting in ink and the like which comprises brominated trisodium phosphate in dilute aqueous solution.

3. The process of making a bleaching solution adapted for the removal of stains,

handwriting in ink and the like which comprises reacting on an aqueous solution containing about six per cent of trisodium phosphate with approximately one per cent of bromine.

4. The process of making a bleaching solution adapted for the removal of stains, handwriting in ink and the like which comprises treating pure trisodium phosphate in distilled water with pure bromine whereby catalysts affecting the stability of the solution are avoided.

5. As a stain remover and ink eradicator brominated alkaline phosphate in aqueous solution free from catalysts causing instability. 15

In testimony, that I claim the invention set forth above I have hereunto set my hand this 20th day of December, 1923.

HARRY M. WEBER.
